G. WYLLIE, JR.

SHAPE RETAINING RING FOR CAPS

Filed June 16, 1924

FIG. 2.

FIG. 3.

FIG. 4.

INVENTOR

GEORGE WYLLIE, JR.

BY *Harold L. Shipman*

ATTORNEY

UNITED STATES PATENT OFFICE.

GEORGE WYLLIE, JR., OF MONTREAL, QUEBEC, CANADA.

SHAPE-RETAINING RING FOR CAPS.

Application filed June 18, 1924. Serial No. 720,350.

To all whom it may concern:

Be it known that I, GEORGE WYLLIE, Jr., a citizen of Dominion of Canada, and resident of Montreal, Maisonneuve, in the county of Hochelaga and Province of Quebec, Dominion of Canada, have invented certain new and useful Improvements in a Shape-Retaining Ring for Caps, of which the following is a specification.

10 This invention has relation to certain new and useful improvements in a shape retaining ring for caps and has for its primary object the provision of a ring of this character which is adjustable to caps of different sizes.

Another object of the invention resides in the provision of an adjustable shape retaining ring for caps which is of a simple and inexpensive construction, light in weight, may be readily inserted, adjusted or removed as desired and when adjusted will be firmly held in its adjusted position by a sleeve surrounding the adjustable bar of the ring.

25 The invention has for a further object the provision of a shape retaining ring for caps in which the reduced overlapped ends may be readily adjusted upon one another and secured in adjusted position while the 30 ring is in use.

With the foregoing and other objects in view, as will appear as the description proceeds, the invention consists of the novel construction, combination and arrangement 35 of co-operating elements, as hereinafter more specifically set forth, claimed and shown in the accompanying drawings forming a part of the present application and in which:

40 Fig. 1 is a section through a cap with the improved ring positioned therein.

Fig. 2 is a plan of the ring, removed.

Fig. 3 is an enlarged sectional view substantially on the plane of line 3-3 of Fig. 45 2, looking in the direction indicated by the arrows.

Fig. 4 is a plan view of the adjustable bar of the ring with the slidable sleeve shown in section, for the sake of clearness.

50 Referring more in detail to the drawings in which similar reference characters designate corresponding parts throughout the several views, it will be understood that the ring 5 may be formed of wicker or other suitable material and may be rounded, as shown in the

drawings or of any other appropriate shape in cross-section. The ends 6 and 7 of the ring 5 are reduced by cutting away approximately one-half thereof, longitudinally, the upper half of the lower end 6 being cut away 60 while the lower half of the upper end 7 is cut away, as shown clearly in Fig. 3. An adjusting and retaining member 8 in the form of a pin and composed of an appropriate spring metal, is provided on the upper face of the upper end 7 and has one end 9 flattened with the rivet 10 extended transversely or vertically through the reduced end 7 of the ring 5. A washer 11 or the like is also preferably provided on the lower 70 end of the rivet 10. The pin 8 is then extended along the upper face of the ring end 7 toward the free extremity thereof and the front end 12 of the pin directed downwardly through the guide opening 13 provided for this purpose in the ring end 7, near the free extremity of the latter. The extremity or point 14 of the pin 8 is suitably tapered so as to bite into the upper face of the lower ring end 6, as illustrated in Fig. 3, after adjustment of the ring ends 6 and 7 on one another to increase or decrease the diameter of the ring 5 and thereby properly adjust the ring to the size hat in which it is positioned.

An arcuate or curved sleeve 15 is slidable on the ring 5 and is formed of metal or other appropriate material. The sleeve 15 has a sufficiently tight fit to firmly hold its position on the ring when located thereon so as 90 to surround and completely enclose the ring ends 6 and 7 and the pin 8, after adjustment of the ring. The sleeve 15 also serves to hold firmly in position the pin 8 and thereby prevent accidental slipping of the ring ends 95 6 and 7 upon one another while the ring is in use within the cap 16, as shown in Fig. 1.

It is believed the construction and operation of the invention may now be understood from the foregoing paragraphs taken in connection with the accompanying drawings without further detailed description. It may be briefly stated, however, that when inserting the ring 5 in the cap 16 or removing the ring 5, the sleeve 15 may be readily 105 moved to some other position on the main portion of the ring 5 and the ring ends 6 and 7, disengaged from the position shown in Figs. 3 and 4 and the ring considerably compressed to permit the same to readily pass 110

through the narrow portions of the cap and into or out of the enlarged upper portion hereof, as the case may be.

While the preferred embodiment of the invention has been described, it is to be understood that minor changes in the details of construction, combination and arrangement of co-operating elements may be resorted to within the scope of what is claimed without departing from the spirit of the invention.

What I claim as new is:

- 10 1. A shape retaining ring for a cap comprising a transversely split ring having reduced ends arranged for adjustable and overlapping engagement; means carried by one of said ends for engagement with the other of said ends to retain the ring in adjusted position; and a covering sleeve movable on said ring and adapted to be positioned over the adjusted ends thereof to enclose the same and hold the retaining member in operative position.
- 15 20

2. A shape retaining ring for a cap comprising a transversely split ring having portions of its ends cut away to provide for 25 overlapping and adjustable engagement of said ends on one another; one of said ends having an opening extended therethrough; a retaining pin carried on said end and having its free extremity extended through said 30 guide opening and adapted for biting engagement with the other end of the ring to prevent longitudinal movement of said ends on one another after adjustment of the ring to the proper diameter for the size of cap 35 in which the ring is positioned; and a sleeve carried on said ring and adapted to be positioned over the adjusted ends thereof to enclose said ends and the retaining pin and prevent accidental disengagement of the 40 latter.

In testimony whereof, I affix my signature.

GEORGE WYLLIE, JR.
